UNITED STATES PATENT OFFICE.

CLAIBORNE W. GOOCH, OF LYNCHBURG, VIRGINIA, ASSIGNOR TO BURROUGHS ADDING MACHINE COMPANY, OF DETROIT, MICHIGAN, A CORPORATION OF MICHIGAN.

ADDING AND LISTING MACHINE.

No. 925,805.

Specification of Letters Patent.

Patented June 22, 1909.

Application filed March 1, 1909. Serial No. 480,497.

To all whom it may concern:

Be it known that I, CLAIBORNE W. Gooch, a citizen of the United States, residing at Lynchburg, in the county of Campbell and State of Virginia, have invented certain new and useful Improvements in Adding and Listing Machines, of which the following is a specification.

This invention relates to that particular type of adding and listing machine which in the trade is termed a "split and normal" machine because of its capability of being "split" or divided into sections as to its printing mechanism for the listing of two or more columns at once, though such machine normally will operate to the full capacity of its keyboard in listing a single column. For an exemplification of such a machine reference may be had to my prior patent No. 825,205, issued July 3, 1906. The machine shown in this patent besides having the above-mentioned capabilities is also equipped for special manipulation to cause the elimination of total printing at the foot of one of two columns listed under a split adjustment of the machine. Though the special device or coupling of that prior patent which provides for connection or disconnection of impression devices is therein said to be capable of varied arrangement so as to locate the point of split or subdivision between any denominations or decimal places desired, the construction shown in said patent does not provide for varying the location of the so-called split at will by manipulation on the part of the user of the machine but a changed location in that prior construction would require a reassembling of parts. Furthermore, although in that prior patent it is said that more than one of the special devices or couplings might be employed so as to provide for "splitting" or subdividing at more than one point at the same time, yet it was not made optional with the user of the machine to vary the number of points of split or subdivision. The art has, however, already advanced somewhat beyond what is disclosed in said patent for in Letters Patent of Great Britain No. 27,269 of 1907, to George B. Putnam, may be seen a construction applied to the same character of machine as shown in my aforesaid patent, which construction provides for varying the location of the split at the will of the operator and also for correspondingly eliminating total

printing at will under one of two columns listed. In both of these prior constructions elimination of the total printing is only possible under one certain column or columns, no provision being made for selection by the user of the column or columns at the foot of which no total printing is to appear.

One object of the present invention is to provide for all sorts of conditions that may arise in regard to the character of the items listed in different columns so that a total can be printed or not at the foot of any column or columns desired whether located to the right or to the left of the point of split. In other words the invention aims to give the machine unlimited capacity not only as to location of the point or points of split and the number thereof, but also as to whether or not totals will be printed at the foot of the columns. Thus it is proposed to provide for each denominational order or decimal series of amount keys in a multiple key bank machine, except the last such series to the right, a special device for manipulation by the user, which device can be adjusted to any one of three positions, first to permit the normal or customary coöperative action of impression or printing devices which effects the filling in of ciphers in a decimal place or places to the right wherein no digit or digits are to appear, second to eliminate such coöperative action and third to prevent the printing of a total. The adjustment of any such manipulative device to the third position effects the elimination of total printing to the right of the point of split marked or denoted by the particular device so adjusted. To provide for elimination of total printing at the foot of a column at the extreme left or in which imprints are made by reason of depression of amount keys of the left-most bank or series, an additional manipulative device will be provided which is only required to have two adjustments for, as to this left-most bank, there need be no adjustment which, like the second adjustment of the other devices, would discontinue coöperative action of impression devices, because there is no impression device farther to the left. The two adjustments of this extra device will therefore merely provide first for permitting the printing of a total at the foot of the left-hand column and second preventing the printing of such total.

In carrying out the invention in the form

here shown the aim has been to provide a thoroughly practical construction comprising parts easy to manufacture in quantities by well-known processes and easy to assemble in a standard adding and listing machine such as herein shown. It has also been the aim to provide for locating the manipulative devices where they will be most convenient to the user and in such manner that their selection with regard to a desired point or desired points of split will be obvious with reference to the keyboard.

With the above and incidental objects in view the invention consists in certain novel features of construction and combinations of parts, the essential elements whereof are recited in the appended claims and a preferred form of embodiment of which is described in detail hereinafter and fully illustrated in the accompanying drawings forming a part of this specification.

Of said drawings Figure 1 represents in left side elevation an adding and listing machine of the type shown in the above-mentioned patents, the same having applied to it parts for carrying out the present invention, the mechanism throughout being at normal; Fig. 2 is a vertical section of the machine taken from front to rear and looking from the left side; Fig. 3 is a horizontal section taken substantially on the line 3—3 of Fig. 1; Figs. 4, 5 and 6 are similar detail sectional views illustrating the three different adjustments of manipulative devices which control the splitting and total printing, parts being broken out in all these views to provide for a larger scale and at the same time economize space; Fig. 7 is a detail plan view taken substantially on the line 7—7 of Fig. 2; Fig. 8 is a detail vertical section taken substantially on the line 8—8 of Fig. 3; and Figs. 9 to 18 show various examples of work which the machine is adapted to perform.

The machine proper of the type here chosen for purposes of illustration, does not require detailed description. It is the well-known Burroughs machine shown in the above-mentioned patents and as therein stated previously exemplified in both United States and British patents. Certain familiar parts of such machine will, however, be enumerated in order to make clear the mode of co-operation therewith of new parts provided for the purpose of carrying out the present invention.

A segmental series of type plates 618 are as usual carried upon the rear ends of levers 611 whose forward ends carry segmental racks 610 normally upheld by latches 415 and a restoring frame 613. Upon operation of the machine resulting in the lowering of said restoring frame the levers 611 move one step whether or not amount keys are depressed and thus the cipher types are brought to the printing line. In case of depression of

the amount keys the latches 415 release the racks and they descend distances determined by the particular amount keys depressed. The racks co-operate with adding pinions 916 in the usual manner, being engaged therewith during ascent in the case of itemizing and during descent in the case of totaling and clearing and during both descent and ascent in the case of totaling without clearing, *i. e.*, subtotaling. Printing hammers 715 are pivoted as usual upon a cross rod 701 and adapted to be driven against the type plates 618 by driving levers 716 under the impulse of spiral springs 780. A bail 712 normally retracts the driving levers 716 and consequently the hammers, said bail being vibrated in every operation of the machine so as to permit the firing of such hammers as may be released after the said bail has retreated. Latches 717 normally overlie the tips of the driving levers 716 to restrain the hammers, these latches being pivoted upon a cross rod 700. Pawls 718 are pivoted upon the cross bar of a bail 704 which vibrates in each operation of the machine and these pawls are connected with the hammer driving levers 716 by the springs 780 so that said springs, besides actuating the hammers, serve to hold the pawls yieldingly in engagement with the upper edges of the latches in front of shoulders thereon. The forward upturned ends or tails of the pawls lie just in rear of cam edges of the levers 611 so that unless such levers move far enough to present digit types at the printing line the pawls will be disabled when the bail 704 swings forward. Otherwise the pawls act to displace the latches and release the hammer drivers and hammers.

All of the above-designated parts are those familiarly employed in machines of this type and the mode of operation referred to is the familiar one. The common way of providing for the automatic filling in of ciphers was to construct the latches 717 with tails overlying adjacent latches from left to right as referred to in my previous patent, it being obvious that the rocking of a latch by reason of the associated lever 611 having swung to present a digit type at the printing line, would cause the rocking of the adjacent latch to the right if the lever 611 associated with that adjacent latch had only moved to present a cipher type at the printing line. In carrying out the present invention such overlying tails are dispensed with and connections provided between the latches which may or may not cause the successive tripping. Thus to each latch to the rear of the shaft 700 there is pivotally attached an irregular-shaped bar or pitman 2 which extends up between the levers 611 and through apertures in a guide plate 3 secured at the top of the machine in rear of the keyboard. Portions of these pitmen protruding upwardly through said guide

plate are shouldered on the left-hand side as clearly shown in Fig. 8 and the pitmen are likewise shouldered on the right-hand side. The pitmen lie edge to edge and the last-
5 mentioned shoulders 4 are normally flush with the upper surface of the plate 3 and such shoulders of all the pitmen except the right-most one confront the upper shoulders 5, a lower shoulder 4 of one pitman confronting an upper shoulder 5 of the next adjacent pitman to the right but with a considerable space between.

Between the usual key-board plates 212 and 213 are arranged slide strips 6 extending 15 from front to rear and each having pivoted to its rear end a piece 7 extending between adjacent pitmen 2 through the spaces bounded top and bottom by the before-mentioned shoulders 4 and 5. These pieces 7 have wide portions 7^a adapted to completely 20 fill such spaces but just forward of such wide portions are narrow portions or necks 7^b. So long as the wide portions 7^a occupy said spaces it will be seen that the lifting of a pit-
25 man by reason of the rocking of its latch will cause its shoulder 4 to lift the filler piece 7 and through the latter the adjacent pitman to the right and so on through the series, the effect produced being the same as that in the
30 case of the common overlapping tails hereinbefore mentioned. Any filler piece 7 may, however, be moved rearwardly by its slide strip 6, the bottom of the wide part 7^a sliding on the upper surface of the plate 3 and such
35 movement carrying said wide part out of the space between the pitman leaving only the narrow part or neck 7^b in such space as shown in Fig. 5. Then the lifting of the associated pitman would not result in the lifting of the
40 pitman to the right for the lower shoulder 4 would have a space to move through and that space bounded at the top by the under-edge of the narrow portion or neck 7^b, is sufficient to provide for full independent movement of
45 the pitman and its latch. Thus the tripping for cipher printing purposes would be prevented and the so-called split established. Of course it will be obvious that with a slide strip 6 and filler piece 7 for each bank of keys
50 a split can be located at any point desired and furthermore any number of points of split can be established and any desired combinations of points of split for different kinds of tabulating work.

55 Coming now to the matter of eliminating total imprints the numeral 227 designates the usual total key bell crank lever connected by a link 911 with pitman 914, and 227^a designates the subtotal bell crank lever operating upon the total bell crank lever through the medium of a bar 227^a, Fig. 1. A rearwardly-extending link 226^a coupled to the bell crank lever 227 is pivotally connected with a depending arm 9 of a yoke frame 10
65 loosely journaled on the rock shaft 207 which

carries the usual key-restoring bail. Said yoke frame has a rearwardly-projecting arm 11 to which is pivotally connected the upper end of a link 12, the lower end of which is pivotally connected to an arm 13 secured to a 70 rock shaft 14, which rock shaft carries a similar arm at its right-hand end, (dotted lines, Fig. 2). To the forward extremities of the arms 13 are pivotally connected rods 15 which extend up in rear of the middle portion of the plate 3 and are secured to a horizontally-disposed cross head or bar 17, the latter having depending guide studs 18 working in apertures of said plate 3, (Fig. 3). Said bar is preferably made angular throughout its middle portion for strength. It will be obvious, that through the above-described connections depression of either the total or subtotal key will result in the lifting of said cross head or bar 17 and that the release of either total or subtotal key and its return to normal will be accompanied by the lowering of said cross head or bar though in order not to impose too much work upon the usual spring which returns the total keys an 80 additional spring 19 will preferably be connected to an upstanding arm 20 on the rock shaft 14 as shown in Fig. 1.

The filler pieces 7 in rear of their wide portions 7^a are formed with shoulders 7^c adapted when the filler pieces are moved to their extreme rearward position to engage over the cross head or bar 17 as shown in Fig. 6. It will be obvious that when so engaged with such cross head or bar lifting of the 100 latter will cause an upward swing of the filler piece which, acting upon the upper shoulder 5 of the associated pitman will lift the same and thus displace the corresponding latch 717 prior to the commencement of 105 an operation of the machine. Consequently when such operation begins and the bail 712 retreats it will be followed by the hammer driver and the hammer will move rearward without a percussive action and without 110 effecting an imprint. This general mode of disabling hammers is explained in the before-mentioned Letters Patent of Great Britain. It is obvious of course that the 115 lifting of a latch in this manner will cause the lifting of latches to the right and elimination of imprints throughout a section or subdivision.

The slide strips 6 are preferably arranged to be manipulated from the front part of the 120 keyboard. As the pitmen are necessarily closely assembled the slide strips, if extending simply in line therewith, would be difficult to separately manipulate. Consequently, they are variously off-set, as clearly 125 shown in Fig. 3, the off-set portions of the two outside strips extending between stems of the amount keys 293. It will be seen that this provides for spreading apart the forward ends of the strips far enough for con- 130

venient separate manipulation. At their forward ends these strips have small studs 21 engaging corrugated flat springs 22 each having three depressions to provide for 5 three different positions of the slide strips. The latter furthermore have lugs 23 on their upper sides seating in sockets of blocks 24 from which project upwardly finger pieces 25 through slots in a cover plate 26. The 10 latter as shown in Fig. 3 is suitably inscribed with numerals to denote the different slide strips as belonging to different denominational orders or decimal series of amount keys. Furthermore, there is inscribed upon 15 this plate in vertical series the words "Normal", "Split" and "No total." With the finger pieces at the forward ends of their slots as shown in Fig. 3 the machine is normal, that is to say operates in the ordinary 20 way to simply list one solid column. To provide for a split at any point the appropriate finger piece is pushed back to the middle position alinement with the inscription "Split". Should it be desired to eliminate 25 the total to the right of any such point of split then the finger piece is moved all the way back or to a position in alinement with the inscription "No total". In order to provide for elimination of the total in an 30 extreme left-hand column an extra slide strip 6^a is provided which has at its rear end a filler piece 7^e of the same construction as the previously-described filler pieces but normally occupying a position farther rear- 35 ward, that is to say a position corresponding with the split position of any of the other filler pieces. The finger piece 25^a of this extra slide strip projects through a shorter slot in the plate 26, there being no occasion, 40 for this extra finger piece occupying a position corresponding with the foremost positions of the other finger pieces. When pushed rearward this extra finger piece 25^a carries its slide and filler piece rearward to 45 connect with the cross head or bar 17. The series of blocks 24 are conveniently assembled over a guiding cross-rod 27, and the top keyboard plate 212 is opened up or slotted sufficiently to receive them and allow for 50 the necessary sliding movement.

It will be noted that the form of means throughout and the relative arrangement are such as to interfere with none of the regular parts of the machine and also such as to 55 present no serious problems in the matter of assemblage, while at the same time no appreciable extra space is required to accommodate the new parts and they are easily accessible. It will further be seen that the primary object of providing unlimited facilities in the 60 way of location and number and combinations of "splits" and elimination of total imprints, is thoroughly accomplished by the above-described construction. Also it is to 65 be observed that the special keys or finger

pieces are located at the top of the machine along the front where they can be most conveniently manipulated and where they can be most intelligently used as related denominational keys. 70

While the above-described construction is thus well adapted to fulfil the various objects stated at the outset, it must be borne in mind that the invention is not necessarily limited to the particular form of embodiment 75 here shown but considerable modification may be practiced and much variation in adaptation to different types of machines, without going outside the scope of the invention. 80

What I claim is:

1. In a machine of the character described, the combination of impression devices co-operatively related for automatic filling in of ciphers, means for interrupting at will the 85 co-operative relationship at a predetermined point or decimal place, total printing means, and means for preventing the printing of a total at will to either side of the point of interruption. 90

2. In a machine of the character described, the combination of impression devices co-operatively related for automatic filling in of ciphers, means for interrupting at will the 95 co-operative relationship at a predetermined point or decimal place, total printing means, and means for preventing the printing of a total at will to either side or on both sides of the point of interruption. 100

3. In a machine of the character described, the combination of impression devices co-operatively related for automatic filling in of ciphers, means for interrupting at will the 105 co-operative relationship at two or more different points or decimal places at once to provide for printing three or more columns, total printing means, and means for preventing the printing of a total to either side of either point of interruption. 110

4. In a machine of the character described, the combination of impression devices co-operatively related for automatic filling in of ciphers, plural means independently operable for interrupting at will the co-operative relationship at two or more different points 115 or decimal places at once to provide for printing three or more columns, total printing means, and means for preventing the printing of a total to either side of either point of interruption. 120

5. In a machine of the character described, the combination of impression devices co-operatively related for the automatic filling in of ciphers, means adjustable to interrupt such co-operative action at two or more points 125 or decimal places at once and further adjustable to provide for elimination of total printing, and totaling devices co-operating with said adjustable means. 130

6. In a machine of the character described,

- the combination of impression devices co-operatively related for the automatic filling in of ciphers, means adjustable to interrupt such coöperative action at two or more 5 points or decimal places at once and further adjustable to provide for elimination of total printing to either side of either point of interruption, and totaling devices coöperating with said adjustable means.
10. 7. In a machine of the character described, the combination with printing hammers and their restraining latches; of connecting means between the latches for causing one to trip another, said means including movable 15 members independently manipulative which when displaced interrupt such successive tripping and said members being further displaceable, and totaling mechanism with connections for coöperating with any such 20 further displaced member or members to trip latches.
8. In a machine of the character described, the combination of a battery of spring-actuated printing hammers, hammer-retracting 25 means, latches for restraining said hammers, means for individually tripping latches when the retracting means have retreated, connecting means between the latches for causing one to trip another, said latter means including 30 movable members independently manipulative which when displaced interrupt successive tripping of one latch by another at two or more different points, and said members being further displaceable, and totaling mechanism 35 with connections for coöperating with any such further displaced member or members to trip latches while the hammers are held back by the retracting means.
9. In a machine of the character described, 40 the combination of printing hammers, latches normally restraining the same and having parts with confronting portions spaced apart to provide for independent movement of any latch, means for individually displacing the 45 latches, and separately manipulative filler pieces normally occupying the spaces between the confronting portions of the latch parts to provide for the displacement of latches one by another, said filler pieces being 50 movable to open such spaces and interrupt such inter-displacing action.
10. In a machine of the character described, 55 the combination of printing hammers, latches normally restraining the same and having parts with confronting portions spaced apart to provide for independent movement of any latch, means for individually displacing the 60 latches, and separately manipulative slides carrying movably mounted filler pieces normally occupying the spaces between the confronting portions of the latch parts to provide for the displacement of latches one by another, said filler pieces being movable 65 to open such spaces and interrupt such inter-displacing action and being further movable to co-act with totaling connections, and totaling mechanism with connections for acting on any filler piece or pieces so further 70
11. In a machine of the character described, the combination of printing hammers, latches normally restraining the same and having parts with confronting portions spaced apart to provide for independent movement of any latch, means for individually displacing the 75 latches, and separately manipulative slides carrying pivotally mounted filler pieces normally occupying the spaces between the confronting portions of the latch parts to provide for the displacement of latches one by another, movement of such filler pieces by the slides opening such spaces to interrupt the inter-displacing action of the latches. 80
12. In a machine of the character described, the combination of printing hammers, pivoted latches restraining the same, pitmen coupled to said latches respectively and adjacent pitmen having confronting edges spaced apart, and slides having filler pieces 85 normally occupying the spaces between such confronting edges but movable by the sides to open such spaces; substantially as and for the purpose described. 90
13. In a machine of the character described, the combination of printing hammers, pivoted latches restraining the same, pitmen coupled to said latches respectively and adjacent pitmen having confronting edges 95 spaced apart, independently movable slides, and filler pieces pivoted thereto and normally occupying the spaces between such confronting edges but movable by the slides to open such spaces; substantially as and for the purpose described. 100
14. In a machine of the character described, the combination of printing hammers, pivoted latches restraining the same, pitmen coupled to said latches respectively and adjacent pitmen having confronting edges 105 spaced apart, independently movable slides, and filler pieces pivoted thereto and extending between adjacent pairs of pitmen and having wide portions normally filling the spaces between the confronting edges of the 110 pitmen and narrow portions adapted to permit independent movement of pitmen when the slides are shifted. 115
15. In a machine of the character described, the combination of a battery of spring-actuated printing hammers, hammer-retracting means, latches for restraining said hammers, means for individually tripping latches when the retracting means have retreated, latch parts having confronting portions spaced 120 apart, separately manipulative filler pieces normally occupying the spaces between the confronting portions of the latch parts to provide for the displacement of latches one by another, said filler pieces being movable 125 to open such spaces and interrupt such inter-displacing action and being further movable to co-act with totaling connections, and totaling mechanism with connections for acting on any filler piece or pieces so further 130

323,356
6 moved, to displace latches while the hammers are held back by the retracting means.

16. In a machine of the character described, the combination of a battery of spring-actuated printing hammers, hammer-retracting means, latches for restraining said hammers, means for individually tripping latches when the retracting means have retreated, latch parts having confronting portions spaced apart, separately manipulative slides carrying movably mounted filler pieces normally occupying the spaces between the confronting portions of the latch parts to provide for the displacement of latches one by another, movement of such filler pieces by the slides opening such spaces to interrupt the inter-displacing action of the latches and further movement of the slides bringing the filler pieces into coöperative relation with totaling connections, and totaling mechanism with connections for acting on any filler piece or pieces so further moved, to displace latches while the hammers are held back by the retracting means.

17. In a machine of the character described, the combination of a battery of spring-actuated printing hammers, hammer-retracting means, latches for restraining said hammers, means for individually tripping latches when the retracting means have retreated, latch parts having confronting portions spaced apart, separately manipulative slides carrying pivotally mounted filler pieces normally occupying the spaces between the confronting portions of the latch parts to provide for the displacement of latches one by another, movement of such filler pieces by the slides opening such spaces to interrupt the inter-displacing action of the latches and further movement of the slides bringing the filler pieces into coöperative relation with totaling connections, and totaling mechanism with connections for acting on any filler piece or pieces so further moved, to displace latches while the hammers are held back by the retracting means.

18. In a machine of the character described, the combination of a battery of spring-actuated printing hammers, hammer-retracting means, pivoted latches for restraining said hammers, means for individually tripping latches when the retracting means have retreated, pitmen coupled to said latches respectively and adjacent pitmen having confronting edges spaced apart, slides having filler pieces normally occupying the spaces between such confronting edges but movable by the slides to open such spaces and further movable by the slides to co-act with totaling connections, and totaling mechanism with connections for acting on any filler piece or pieces so further moved, to displace latches while the hammers are held back by the retracting means.

19. In a machine of the character described,

the combination of a battery of spring-actuated printing hammers, hammer-retracting means, pivoted latches for restraining said hammers, means for individually tripping latches when the retracting means have retreated, pitmen coupled to said latches respectively and adjacent pitmen having confronting edges spaced apart, independently movable slides, and filler pieces pivoted thereto and normally occupying the spaces between such confronting edges but movable by the slides to open such spaces and further movable by the slides to co-act with totaling connections, and totaling mechanism with connections for acting on any filler piece or pieces so further moved, to displace latches while the hammers are held back by the retracting means.

20. In a machine of the character described, the combination of a battery of spring-actuated printing hammers, hammer-retracting means, pivoted latches for restraining said hammers, means for individually tripping latches when the retracting means have retreated, pitmen coupled to said latches respectively and adjacent pitmen having confronting edges spaced apart, independently movable slides, and filler pieces pivoted thereto and extending between adjacent pairs of pitmen and having wide portions normally filling the spaces between the confronting edges of the pitmen and narrow portions adapted to permit independent movement of pitmen when the slides are shifted, said filler pieces being further shiftable by the slides and having shoulders to then co-act with totaling connections, and totaling mechanism with connections for acting on any filler piece or pieces so further moved, to displace latches while the hammers are held back by the retracting means.

21. In a machine of the character described, the combination of a battery of spring-actuated printing hammers, hammer-retracting means, pivoted latches for restraining said hammers, means for individually tripping latches when the retracting means have retreated, pitmen coupled to said latches respectively and adjacent pitmen having confronting edges spaced apart, independently movable slides, and filler pieces pivoted thereto and extending between adjacent pairs of pitmen and having wide portions normally filling the spaces between the confronting edges of the pitmen and narrow portions adapted to permit independent movement of pitmen when the slides are shifted, said filler pieces being further shiftable by the slides and having shoulders to then co-act with totaling connections, and totaling mechanism with connections for acting on any filler piece or pieces so further moved, to displace latches while the hammers are held back by the retracting means, said connections including a reciprocating bar adapt-

ed to act upon the shoulders of the filler pieces.

22. In a machine of the character described, the combination of a battery of spring-actuated printing hammers, hammer-retracting means, pivoted latches for restraining said hammers, means for individually tripping latches when the retracting means have retreated, pitmen coupled to said latches respectively and adjacent pitmen having confronting edges spaced apart, independently movable slides, and filler pieces pivoted thereto and extending between adjacent pairs of pitmen and having wide portions normally filling the spaces between the confronting edges of the pitmen and narrow portions adapted to permit independent movement of pitmen when the slides are shifted, said filler pieces being further shiftable by the slides and having shoulders to then co-act with totaling connections, and totaling mechanism with connections for acting on any filler piece or pieces so further moved, to displace latches while the hammers are held back by the retracting means, said mechanism and connections comprising a key lever, a bell crank, a link connecting the latter with the key lever, a rock frame connected with the bell crank, rods supported by the rock frame, and a cross-bar carried by the rods and adapted to act upon the shoulders of the filler pieces.
23. In a machine of the character described, the combination of keyboard plates, rows of amount keys therein extending from front of rear, slide strips or bars extending from front

to rear between the plates and having handles or finger pieces protruding from the upper keyboard plate at the front, printing devices co-operatively related for the filling in of ciphers, and means connected with the rear ends of said slide strips for interrupting the co-operative action at one or another point.

24. In a machine of the character described, the combination of keyboard plates, rows of amount keys therein extending from front to rear, special keys protruding at the front of the upper keyboard plate, operating connections extending from said special keys rearward under said plate, printing devices co-operatively related for the filling in of ciphers, and means operated by said connections to interrupt the co-operative action at one or another point.

25. In a machine of the character described, the combination of a top plate, rows of amount keys extending from front to rear thereof, special keys along the front of said plate, slide strips or bars extending rearwardly from said special keys under said plate, coupling devices connected to said strips or bars to the rear of the amount keys, and printing devices below said coupling devices and comprising latches connected therewith.
